(57) **CLAIM**

The ornamental design for a jewelry bead, as shown and described.

DESCRIPTION

FIG. 1 is a front perspective view of a jewelry bead showing my new design;

FIG. 2 is a front elevational view of the jewelry bead of FIG. 1;

FIG. 3 is a rear elevational view of the jewelry bead of FIG. 1;

FIG. 4 is a top plan view of the jewelry bead of FIG. 1;

FIG. 5 is a bottom plan view of the jewelry bead of FIG. 1;

FIG. 6 is a right side plan view of the jewelry bead of FIG. 1;

FIG. 7 is a left side plan view of the jewelry bead of FIG. 1;

FIG. 8 is a cross-sectional view of the jewelry bead of FIG. 1, taken along section line 8-8 as shown in FIG. 4;

FIG. 9 is a sectional perspective view of the jewelry bead of FIG. 1, taken along section line 8-8 as shown in FIG. 4;

FIG. 10 is a cross-sectional view of the jewelry bead of FIG. 1, taken along section line 10-10 as shown in FIG. 4;

FIG. 11 is a sectional perspective view of the jewelry bead of FIG. 1, taken along section line 10-10 as shown in FIG. 4;

FIG. 12 is a perspective view of the jewelry bead of FIG. 1, with the jewelry bead secured to a portion of a necklace; FIG. 13 is a perspective view of the jewelry bead of FIG. 1, with the jewelry bead secured on a portion of a bracelet; FIG. 14 is a perspective view of the jewelry bead of FIG. 1, with the jewelry bead secured on a bracelet; and,

FIG. 15 is a perspective view of the jewelry bead of FIG. 1, with the jewelry bead secured on a portion of a necklace. The broken lines in FIGS. 12-15 depict environmental subject matter and form no part of the claimed design.
